METHOD OF MAKING SHOES

David H. Finberg and Joseph Arthur Gagnon,
Worcester, Mass., assignors to B-W Footwear
Co. Inc., Worcester, Mass., a corporation of
Massachusetts

Application January 2, 1934, Serial No. 704,880

3 Claims. (Cl. 12—142)

This invention relates to shoes and slippers and to methods of making the same.

It is the general object of our invention to provide a new construction of shoe or slipper, in which the upper, insole and out-sole are secured together in a new and improved manner.

A further object is to provide an improved method of making the shoe and assembling and securing the parts thereof together, by the use of which method marked economy of manufacture is attained. The shoe or slipper thus constructed is of attractive appearance and possesses excellent wearing qualities.

Our invention further relates to arrangements and combinations of parts which will be herein-after described and more particularly pointed out in the appended claims.

Preferred forms of the invention are shown in the drawings, in which

Fig. 1 is a side elevation of a special last used in carrying out our invention;

Fig. 2 is a transverse sectional view thereof, taken along the line 2—2 in Fig. 1;

Fig. 3 is a bottom view thereof;

Fig. 4 is a bottom view of the insole used in our improved shoe;

Figs. 5 and 6 are sectional views similar to Fig. 2 but showing successive steps in assembling the insole and upper on the last;

Fig. 7 is a bottom view, looking in the direction of the arrow 7 in Fig. 6;

Fig. 8 is a sectional view of the insole and upper after removal from the special last;

Fig. 9 is a view similar to Fig. 8 but showing the parts stitched together;

Fig. 10 is a bottom view of the partially formed shoe, looking in the direction of the arrow 10 in Fig. 9;

Fig. 11 is a sectional view similar to Fig. 8 but showing a modified construction;

Fig. 12 is a bottom view, looking in the direction of the arrow 12 in Fig. 11;

Fig. 13 is a view of the parts shown in Figs. 11 and 12, assembled on a regular or standard last;

Fig. 14 is a plan view of the out-sole used in our improved shoe;

Fig. 15 is a sectional view similar to Fig. 13, but after the filler and out-sole have been secured in place;

Fig. 15^a is a detail sectional view similar to Fig. 15 but showing a slight modification;

Fig. 16 is a detail sectional view showing the shoe removed from the last and with the sock lining inserted;

Fig. 17 is a bottom view, looking in the direction of the arrow 17 in Fig. 15 and with a portion of the out-sole broken away;

Fig. 18 is a side elevation of the shoe, looking in the direction of the arrow 18 in Fig. 17;

Fig. 19 is a plan view of a recessed insole member;

Figs. 20 and 21 are detail sectional views illustrating successive steps in assembling the recessed insole member in a shoe;

Fig. 22 is a detail sectional view showing a further slightly modified construction;

Fig. 23 is a bottom view of a partially formed shoe showing another modification;

Fig. 24 is a partial bottom view of a last to be used in this modified construction, and

Fig. 25 is a side elevation of the latter shoe, looking in the direction of the arrow 25 in Fig. 23.

Referring to the drawings, our improved method of making a shoe or slipper involves the use of a special or preliminary last L, shown in detail in Figs. 1, 2, 3 and 24.

This special last L comprises an upper part or body portion 25 of standard shape and commonly made of hard wood. A metal plate 26 is permanently secured to the bottom of the last and extends beyond the edges of the last, thus providing a flange portion or projection 27. This flange may extend entirely around the last as shown at 27_a in Fig. 24 or may be confined to the front and shank portion as indicated at 27 in Fig. 3. This metal plate 26 or 26_a is provided with the usual openings 28 through which the insole member may be tacked to the last.

In making a shoe by our improved method, we first take an oversize insole 30 (Fig. 4) of any suitable material, such as fibre board. This material should be relatively thin but of substantial stiffness. Before assembling the insole 30 on the last L or L', we apply a coating of a suitable cement around the edge of the insole on the bottom face thereof, as indicated at 31 in Fig. 4.

We then secure the insole 30 to the bottom of the last by tacks 32 (Figs. 5 and 7), it being essential that the insole shall be of the exact outline of the metal plate 26 and that the edge of the insole shall coincide with the edge of the plate.

We next assemble the upper 33 on the last L, bringing the edge portion 34 of the upper around the edge of the last plate 26 and insole 30, and pressing it firmly against the cemented portion 31 of the bottom of the insole. Preferably the edge portion of the upper is given a cement coating before the parts are assembled.

We then remove the tacks 32 and draw the special last L out of the partially assembled shoe, leaving the upper 33 and insole 30 in the assembled relation shown in Fig. 8.

We then insert a row of stitching 36 (Figs. 9 and 10) around the edge of the insole and upper, thus binding the doubled edge portion of the upper 33 around the edge portion of the insole 30 and securing it at both faces of said insole.

During this stitching operation, we may, if de-

sired, feed a strip of tape or binder 37 (Figs. 11 and 12) into the stitching machine, guiding it in such a way that it will be secured around the combined edge portions of the upper and insole, thus effectively concealing the upper along the edge of the insole. The ends of the tape or binder 37 are preferably left loosely projecting as indicated in Fig. 12, for a purpose to be described.

Having assembled the insole and upper as shown in Fig. 9 or 11, and with or without the binder 37, we then insert a regular last R in the assembled parts, and last and tack the heel portions in the usual manner. This heel lasting operation in itself forms no part of our present invention and is not indicated in the drawings, but will be readily understood by those skilled in the art.

We then preferably insert a filler F (Fig. 15) in the recess below the insole 38, and secure an out-sole S to the assembled shoe parts in any usual manner. The filler F may be a piece of felt or may be of any other suitable material. The outsole S may be of any suitable material such as rubber or composition, and may have a coating 48 of cement around the edge portion of the sole S on the upper face thereof, this being provided before assembling the sole on the shoe.

We then preferably insert a second row of stitching 42 around the edge of the shoe, the stitches extending through the out-sole, the edge portions of the insole and upper, and also through the binder 37 if used.

We then complete the lasting of the heel portion of the shoe in the usual manner, remove the last from the shoe and apply a heel H (Fig. 18) thereto if desired.

Prior to assembling the out-sole S on the shoe, the end portions 43 (Fig. 17) of the binder 37 are turned inward over the heel portion of the insole, so as to produce a finished effect at the rear of the shank, as indicated at 44 (Figs. 17 and 18).

The shoe may then be removed from the last and a sock lining 45 (Fig. 16) may be inserted, thus completing the structure of the sole portion of the shoe.

While we have shown the stitching 42 as extending directly through the outer sole, it will be understood that the out-sole may be skived or slitted and that the stitches may be concealed as in the usual welt shoe, this construction being indicated at 47 in Fig. 15.

In Figs. 19, 20 and 21 we have indicated a modified construction in which a recessed insole member 50 is substituted for the complete insole 38. The insole member 50 is placed against the last plate 26 and is secured to the upper 33 as in the construction previously described.

While certain of the advantages of our invention may be attained by proceeding as indicated in Figs. 19 to 21, the construction first described is ordinarily preferred.

In Fig. 22 we have shown a slight additional modification in which the insole 38 is provided with a sock lining 52 secured thereto before the insole 38 is applied to the last. This lining extends to the edge of the insole, so that the lining is stitched into the shoe during the assembly of the parts thereof.

In Fig. 3 we have shown the flange 27 extending around the front and shank portions only of the last, the rear portion of the shoe being lasted and assembled in the usual manner. We

may, however, extend the flange around the heel portion of the last also, as shown at 27a in Fig. 24, in which case the bottom of the partially formed shoe on removal from the special last will have the appearance indicated in Fig. 23 rather than that indicated in Fig. 10.

When thus constructed with a continuous projecting edge portion, the shoe in side elevation will appear as indicated in Fig. 25, with the binder 37 forming a contrasting edge portion entirely around the shoe. It will be understood that the construction indicated in Fig. 9 may also be extended entirely around the shoe, the binder being omitted.

Having thus described our invention, it will be evident that a shoe constructed in accordance with our invention will have all parts thereof firmly secured and that the shoe will possess substantially all of the advantages of a welt construction, while the use and cost of a welt or rand is entirely avoided.

The described method of making a shoe may be performed commercially with ease and rapidity and with marked economy as compared with the more usual methods of making shoes of corresponding grade.

In the claims, the term "insole" is to be understood as including also the recessed insole member 50.

Having thus described our invention and the advantages thereof, we do not wish to be limited to the details herein disclosed, otherwise than as set forth in the claims, but what we claim is:

1. The method of making a shoe which comprises assembling an insole and upper on a special last having a bottom flange projecting beyond the edge of the last, folding the edge of the upper around said flange and insole, cementing the edge of the upper to the bottom surface of the insole, removing the special last, stitching the upper and insole together along the cemented edge portions, inserting a regular last, and positioning and securing an out-sole on said assembled shoe parts.

2. The method of making a shoe which comprises assembling an insole and upper on a special last having a bottom flange projecting beyond the edge of the last, folding the edge of the upper around said flange and insole, cementing the edge of the upper to the bottom surface of the insole, removing the special last, stitching the upper and insole together along the cemented edge portions, inserting a regular last, positioning an out-sole on said assembled shoe parts, and stitching said out-sole to the edge portions of said insole and upper.

3. The method of making a shoe which comprises assembling an insole and upper on a special last having a bottom flange projecting beyond the edge of the last, folding the edge of the upper around said flange and insole, cementing the edge of the upper to the bottom surface of the insole, removing the special last, stitching the upper and insole together along the cemented edge portions and simultaneously securing a binding around said edge portions, inserting a regular last, positioning an out-sole on said assembled shoe parts, and stitching said out-sole to the edge portions of said insole, upper and binding.

DAVID H. FINBERG.
JOSEPH ARTHUR GAGNON.
